UNITED STATES PATENT OFFICE.

FRANCIS WENTWORTH BREWSTER, OF BLOOMSBURY, COUNTY OF MIDDLESEX, ENGLAND.

BUOYANT LIFE-LINE.

SPECIFICATION forming part of Letters Patent No. 292,281, dated January 22, 1884.

Application filed October 15, 1883. (No model.) Patented in England May 10, 1883, No. 2,381.

To all whom it may concern:

Be it known that I, FRANCIS WENTWORTH BREWSTER, of Bloomsbury, in the county of Middlesex, England, a subject of the Queen of Great Britain and Ireland, have invented 5 certain Improvements in Buoyant Devices, of which the following is a specification.

The subject of the present invention is a flexible buoyant life-line, life-coil, or device, 10 made of any desired length and diameter, and of such a flexible formation as will permit of its being quickly wound about the body, or about any article it is desired to render buoyant, or of its being thrown to a man overboard, 15 and of being used as a means of keeping him afloat, and of raising or hauling him up the ship's side.

In the accompanying drawings, Figure 1 is a view, partly in section, of a portion of one 20 form of my buoyant line, and Figs. 2 and 3 similar views of modifications.

The life-line or device may be made, as shown in Fig. 1, by inclosing within a flexible tubing, 1, isolated sections of a filling, 2, of 25 roasted, carbonized, rasped, or water-repellent cork, or of other suitable pliant buoyant means—such as what is known as “elastic cotton”—with a flexible core or center, 3, of rope or cord or other like material, for affording 30 any required strength. In the manufacture of this life-line I insert the core or center throughout the length of the tubing, and close one end of the latter, leaving a length of the core protruding, keeping the core central of 35 the tube. I then ram in the filling of buoyant material until I have filled the length of one section, and I then lash or tie the tubing round with wire or string, as at 4, to isolate the section of filling from the next adjacent one; and 40 I similarly proceed until the desired length of life-line (giving the appearance of a string of sausages) is completed. The sections may be divided off at any suitable intervals apart, either by tying, twisting, stitching, eyeletting, 45 or otherwise securely fastening the tubing across, so as to prevent the buoyant material, or the sections thereof, from shifting, and to attain and preserve a thoroughly-flexible formation, admitting of the life-line being rolled 50 or folded into a very small compass; and to

facilitate this I leave longer spaces between some of the sections than between others, for admitting of the device being completely doubled up in convenient lengths. The inclosing tubing may be made of water-proof 55 material; but it is not essential that it should be. The protruding ends of the core serve as means for tying the life-line about the body of the wearer, and for joining any desired number of lengths of the life-line together. 60

In lieu of filling the buoyant material directly into flexible tubing, it may be filled into separate cases, envelopes, or cartridges 5, which may then be inserted endwise into tubing 1, 65 the cartridges being isolated and the desired flexibility attained by contracting and fastening the tubing across, as hereinbefore described, as shown in Fig. 2. This figure represents the formation of the life-line without 70 a central core, and this formation would be serviceable where less strength is required; but a continuous core may be passed throughout the length of the line thus formed with cartridges. 75

At convenient intervals apart the device may be provided with projecting ends 6, or other fastening means for securing the same in position about the body after being coiled.

When using solid means of buoyancy, as 80 shown in Fig. 3, I do not need, though I may use, an outer covering or tubing, as the flexible life-line may be made by threading a series of corks, 7, upon a core or center, knotting the latter between the sections, or placing 85 small beads 8, of wood or cork, between them to obtain the necessary flexibility.

Any desired length of life-line may be made in one continuous length, or by permanently or detachably connecting separate buoyant 90 sections or series thereof into a continuous life-line of any required length. When forming the life-line by filling soft or yielding buoyant material into the tubing, I prefer to make the line of short lengths for facility of ramming in the material, and I then tie or otherwise fasten lengths together by means of the protruding ends of core, or by other fastening means. 95

Such improved buoyant devices, when made 100

of a convenient diameter, can be temporarily worn around the body under any ordinary outer garments during short passages at sea, or when otherwise on the water, and in case of emergency they will thus be available for their intended use without needing any attention.

I am aware that belts and other life-preservers have before been made to be strapped around particular parts of the person; but the peculiarity and special advantages of my present invention consist in the application of buoyant means to a flexible life-line device not made to fit or conform to any part of the person of the wearer, but in the form of a line or rope, capable of being grasped in the hand, and of being readily wound about any part of the wearer and fastened in position, and which, when thrown to a man overboard, will float upon the surface of the water, and when laid hold of by him will serve as a life-buoy, and as a means of hauling him up the ship's side.

I claim as my invention—

1. A flexible buoyant life-line device, consisting of a series of buoyant sections composed of or filled with any suitable buoyant material, in combination with a flexible center or core about which such sections are flexibly connected, end to end, into a continuous life-line of any desired length. 30

2. A flexible buoyant life-line device, consisting of a series of buoyant sections composed of or filled with suitable buoyant material and flexibly connected, end to end, in the form of a line or rope capable of being grasped in the hand, substantially as described. 35

In testimony whereof I have signed my name to this specification in the presence of two subscribing witnesses.

FRANCIS WENTWORTH BREWSTER.
